CHARLES CONNER, OF NEW YORK, N. Y.

WIRE WRAPPING OR COVERING MACHINE.

SPECIFICATION forming part of Letters Patent No. 278,099, dated May 22, 1883.

Application filed April 8, 1882. (No model.)

To all whom it may concern:

Be it known that I, CHARLES CONNER, of the city, county, and State of New York, have invented a new and Improved Wire Wrapping or Covering Machine, of which the following is a full, clear, and exact description.

The object of my invention is to provide a machine by which wire may be wrapped or wound with one or more strips or ribbons of rubber or similar material for insulating or protecting the wire.

In the construction shown in the drawings, when the machine is in full operation, a strip or ribbon of rubber is first wrapped or folded around the wire, so that the edges of the strip will meet or overlap each other along the length of the wire, and then around this strip and the wire is wound spirally another strip of rubber, which latter is done by means of a reel which is carried around the wire, the first strip being applied by drawing the wire and strip together through a suitable eye formed in a fixed eye-plate, which eye closes the strip over the wire. The reel for spirally winding the wire is carried around the wire, preferably by means of a revolving disk situated immediately in the rear of the said fixed eye-plate, through the center of which disk the wire passes into a sleeve which compacts, smooths, and finishes the covering. The disk is journaled upon the end of this sleeve. The eye-plate has a revolving bushing, of rubber or similar material, for preventing injury of the strip of rubber from coming in contact with the eye-plate, and the sleeve has interchangeable bushings, of Babbitt metal or similar material, to suit wires of different sizes and strips of different thicknesses. The strip or ribbon first applied to the wire is fed off from a reel attached to the eye-plate, or to some other stationary object, and thence passes through suitable guides, which turn or roll up the edges of the strip before it reaches the wire and eye, and the wire itself is drawn from a primary reel through the eye and sleeve by means of rubber rollers placed immediately in the rear of the sleeve, from which rollers it passes, completely covered, to the final winding drum or reel at the end of the machine.

Motion is imparted to all of the moving parts of the machine by suitable gearing, which will be hereinafter fully described.

Reference is to be had to the accompanying drawings, forming part of this specification, in which similar letters of reference indicate corresponding parts in all the figures.

Figure 1 is a side elevation of my wire wrapping or covering machine. Fig. 2 is a plan view thereof. Fig. 3 is a detailed face view of the upper end of the eye-plate; and Fig. 4 is a detailed sectional view of the sleeve, showing the bushing thereof.

A represents the eye-plate; B, the revolving disk which carries the reel C; D, the horizontal sleeve upon which the disk B is journaled, and E E' represent the rubber rollers by which the wire F is drawn from the primary reel G through the eye-plate and sleeve, and delivered, after being covered, to the drum H at the rear of the machine, which drum is turned by the belt J, leading from a pulley fixed upon one end of the main power-shaft K, which shaft is journaled in the rear extensions, a a, of the side plates, L L, which side plates constitute the main frame or housing for the power part of the machine.

The power part of the machine consists of the cog-wheel M, secured upon the main power-shaft K, the large cog-wheel N, secured upon one end of the shaft O' of the rubber roller E', which is journaled in the side plates, L L, which large cog-wheel meshes with the wheel M, the large beveled cog-wheel P', secured upon the other end of the said shaft O', which cog-wheel meshes with the beveled horizontal gear Q upon the vertical shaft R, the large beveled cog-wheel S, secured upon said vertical shaft, which cog-wheel meshes with the beveled cog-wheel T upon the horizontal shaft U, the cog-wheel V, which is secured upon the said shaft U and drives the cog-wheel W, and the pulley X, the two latter being secured upon the horizontal shaft Y. The shaft O, upon which the upper rubber roller, E, is secured, receives motion from the shaft O', through the cog-wheel P', (shown in Fig. 1,) secured upon the shaft O', between the beveled gear P and the side piece of the frame, and the cog-wheel Q', se-

cured upon the shaft O, as shown clearly in Fig. 2. This shaft O is not journaled in fixed bearings in the side plates, L L, of the frame, but in the blocks L' L', which are placed in the ways l l of the said plates, which blocks are adapted to be vertically adjusted, by means of the screws d d, for regulating the pressure of the rubber rollers upon the wire.

The disk B, which, as above mentioned, is journaled upon the forward end of the horizontal sleeve D, receives motion from the pulley X, through the band f, which passes over the pulley X, and the pulley b, formed upon the rear face of the disk, and the said sleeve D is held in horizontal position on a line with the eye a' of the eye-plate A and the point of contact with each other of the rubber rollers E E' by the support D' and the plate H', held between the forward extensions, c c, of the side plates, L L, of the main frame, as shown clearly in Fig. 2.

Inside of the sleeve D is placed the tubular bushing e, of Babbitt metal or similar material, which has a longitudinal passage through it of a diameter about equal to or a little less than the diameter of the wire after the ribbons or rubber shall have been applied thereto. There will be several of these bushings, which will be interchangeable with each other, with different-sized passages through them to suit wires of different sizes and various thicknesses of covering.

The eye-plate A is recessed or countersunk around the eye a', as shown at g, to receive and hold the bushing h for protecting the ribbon j, of rubber, as it passes through the eye. This bushing is preferably formed of the two pieces of rubber tubing o o, placed upon the bent wires or small rods k k, the two being adapted to be placed together and put in the recess or countersink g and retained by the buttons i i, or by any other suitable means, so that the tubes o o will revolve on the wires or rods k as the covered wire passes through the eye.

C' is the tension device secured to the disk B, through which the ribbon j', as it winds off from the reel C, passes, and serves as a means for regulating the tightness with which the ribbon will be wound upon the wire; and it consists of a suitable metal plate slotted so as to form several bars over and under more or less of which the ribbon is to be passed, according to the tension required.

In front of the eye-plate A is secured the reel G', upon which the ribbon j, which is wrapped or folded around the wire first, is held, and above this reel, between it and the eye a' of the eye-plate, are secured to the eye-plate the guides f' f', through which the ribbon passes as it leaves the reel G', and which are so formed as to roll or turn up the edges of the ribbon, as clearly illustrated in the drawings, to properly fold over and around the

wire F as the ribbon and wire pass through 65 the eye a'.

Upon the rear side of the eye-plate, immediately below the eye a', is secured the friction-roller g', which serves to support the wire and first wrapping and prevent the same from sagging as they pass from the eye to the sleeve D, as will be clearly understood from Fig. 1.

In use the wire to be covered will be placed upon the primary reel G, and the reels C and G' will be filled with the ribbons j j' of rubber or other material, to be applied to the wire, and the end of the ribbon j and the end of the wire will be passed by the hands of the attendant first through the eye a' of the eye-plate, (the ribbon having first been placed in the guides f'), and then, together with the ribbon j', through the sleeve D and between the rollers E and E', and then attached to the drum H, where they will be held until a belt (coming from a shaft or any motor) is passed from the loose pulley J' to the pulley F', which is fixed upon the main shaft K of the machine. This, through the gearing above described, will impart rotary motion to the rollers E E', reel H, 90 and the disk B, which will carry the reel C around the wire, and will cause the rollers E E' to draw the wire and ribbons slowly through the guides f', eye a', and the sleeve. The guides and eye will cause the ribbon j to be closely wrapped or folded around the wire, and the reel C, moving around the wire and covering j, will cause the ribbon j' to be wound spirally around the covering j and the wire. In passing through the bushing e of the sleeve D 100 (the proper bushing to suit the size of wire and the thickness of the ribbons having been selected and placed in the sleeve) the bushing will compress and smooth down the covering and close the same firmly upon the wire 105 and give the covering a smooth and proper finish.

Having thus fully described my invention, I claim as new and desire to secure by Letters Patent—

1. The combination, with the plate A, provided with the eye a' for folding the covering on the wire, of the sleeve D, the disk B, journaled on the said sleeve, the reel C, secured to the disk, and mechanism for revolving the 115 disk and reel, as set forth.

2. The combination, with the eye-plate A and the rubber rollers E E', of the sleeve D, the disk B, the reel C, and mechanism, substantially as described, for rotating the said 120 rollers and revolving the reel, as set forth.

3. The combination, with the eye-plate A, the reel G', and the guides f', of the reel C, tension device C', and mechanism, substantially as shown and described, for revolving 125 the reel C and drawing the wire through the eye-plate, as set forth.

4. The combination, with the revolving reel

C, of the tension device C', substantially as described.

5. The combination, with the eye-plate A, formed with the eye a', of the guides f' f', substantially as and for the purpose set forth.

6. The combination, with the plate A, provided with the eye a', of rotating bushing arranged in said eye for protecting the ribbon or rubber covering, substantially as described.

7. The bushing for the eye a', formed of the bent wires or rods k k, covered with the rubber tubing o o, substantially as described.

CHARLES CONNER.
